UNITED STATES PATENT OFFICE.

BOWDRY McHATTON, OF ODESSA, MISSOURI, ASSIGNOR OF ONE-THIRD TO GLENN J. HOUGH, OF KANSAS CITY, MISSOURI.

WAGON-BOX.

1,182,285.

Specification of Letters Patent.

Patented May 9, 1916.

Application filed June 27, 1914. Serial No. 847,662.

To all whom it may concern:

Be it known that I, BOWDRY McHATTON, a citizen of the United States, residing at Odessa, in the county of Lafayette and State 5 of Missouri, have invented certain new and useful Improvements in Wagon-Boxes; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to wagon boxes, and has for its object to provide a light, substantial, sheet metal box, having slidable, interlocking joints connecting the different parts, that especially adapt the box for hauling 20 of loose grain, or the like.

In accomplishing this object, I have provided the improved details of structure hereinafter described and illustrated in the accompanying drawings, wherein:—

25 Figure I is a perspective view of a wagon box embodying my invention. Fig. II is a longitudinal, vertical sectional view of the box. Fig. III is a front elevation of the box. Fig. IV is a vertical sectional view 30 of the same. Fig. V is an enlarged detail perspective, showing the slidable, interlocking joint between the side members and end gates. Fig. VI is a sectional perspective, showing the overlapping flanges of the end 35 gate. Fig. VII is a vertical sectional view of one of the central side members.

Referring more in detail to the drawings: 1 designates a wagon body embodying my invention and comprising front 40 and rear cross sills 2, and central cross sills 3, on which are mounted the various box members consisting of a bottom 4, which is preferably formed of a single piece of sheet metal, lower and upper side members 45 5—6, and lower and upper end gates 7—8, all of which parts are held together by interlocking joints and the end cross rods 9.

The cross sills 2—3 consist of downwardly opening, channeled, metallic beams riveted, or otherwise secured to the bottom plate 4, and having their ends projecting beyond the sides of the box and provided near the ends with apertures 10 for receiving rods 11, which are bolted thereto and to

the side member 5, to brace and strengthen 55 the latter.

In order that there may be a tight, grain-proof joint between the bottom and side members, I provide the lower edge of each side member 5 with an outturned flange 12 60 having an inwardly opening socket 13 into which the side edge of the bottom plate 4 is projected, and sealed therein to form a tight closed joint. On the lower edge of the upper side members 6 is an outturned, 65 integrally formed flange 14, which is adapted for slidable mounting within the inwardly opening slot 15 of the upper flange 16 of the side-board 5 to form a closed joint.

The end members 7—8 have at each end an 70 outturned flange 17 slidably mounted within an inwardly opening slot 18, formed by offsetting a portion 19' of plates 19 which are secured on the inner face and at the ends of each side member, the end members being 75 supported in position by angle members 20 that are spaced from the offset plates 19 and secured to the side members. The lower end member 7 consists of a single sheet metal plate having its upper edge bent outwardly 80 and backwardly upon itself forming a flange 21. The upper end member 8 is a single piece of sheet metal having a beaded upper edge and having its lower edge turned 85 inwardly and downwardly and then turned back on itself to form a lip 22, and continued horizontally and turned downwardly to form an outer lip 22', thus forming a channel 22" for receiving the laterally turned flange 21 of the lower end member 7. 90

After the end gates are placed in position, they are held secure by the end rods 9, which project through alining apertures in the side members and the flanges 19', and the outturned flanges 17 of the end gates, which 95 hold the various parts firmly together forming a very rigid body. It will be seen that the flanges of the various side and end members not only serve as joining parts, but also serve as stiffening members for the box, thus 100 making it rigid and substantial.

On each side of the box are placed spacers 23 for engaging the standards of a running gear, and a central side step 24, which is formed between the central cross sills 3 by 105 an outwardly projecting portion of the bottom plate 4 and an overlying outturned portion of the flange 12 of the lower side mem-

ber 5. In order that the box may be held firmly on the running gear, I provide a downwardly opening, channeled member 25 that is secured to the bottom plate 4 and adapted for receiving the rear bolster of a running gear, thereby preventing any backward or forward sliding movement of the box between the standards. I also provide a reinforcing strip 26, which is secured on the under side of and adjacent the back edge of the bottom plate 4, having its outer ends turned upwardly then inwardly, thus overlying the flanges 12, and secured to the side members 5, and the inner edge of said strip 26 is curled to form a sleeve 26' for receiving a rod 27 on which is hinged a downwardly opening, shoveling door 28, and which may also be used to support a skid, or the like. I also provide oppositely disposed seat supporting members 29 secured to the side members, and a seat 30.

Presuming the parts to be constructed and assembled as described, they may be placed on any ordinary running gear and either a single, or a plurality of tiers of side members may be used, as desired. It will be seen that by so constructing the box a substantial, rigid body is secured comprising members that will not warp or split and which are joined by interlocking closed

joints that especially adapt the wagon box to hauling grain or any loose material of a sifting nature.

Having thus described my invention, what I claim as new therein, and desire to secure by Letters-Patent, is:

1. In a wagon box the combination with a bottom plate, of lower side members interlocking with the bottom plate, upper and lower interlocking side members, upper and lower interlocking end members, and means for locking lower end members with lower side members, and upper end members with upper side members.

2. In a metallic wagon box, a lower end member having a lateral, reversely turned flange on its upper edge, and an upper end member having a beaded upper edge and having its lower edge turned inwardly and downwardly then back on itself, then continued horizontally then downwardly, forming a channel for the seating snugly of the upper end member on the lateral flange of the lower end member.

In testimony whereof I affix my signature in presence of two witnesses.

BOWDRY McHATTON.
